UNITED STATES PATENT OFFICE

ALLISON J. THOMPSON, OF CLEVELAND, OHIO

LAMP HANGER STRUCTURE

Application filed October 27, 1930. Serial No. 491,445.

This invention relates to lamp fixtures of the type comprising a main hanger member adapted to be secured as against a ceiling, and a lamp hanger member suspended 5 from the main hanger member to be lowered therefrom as for cleaning or replacement of the lamp carried thereby.

These two principal members of such a lamp fixture are provided with cooperative 10 latch means whereby when the lamp hanger member is in raised position it may be there maintained. To this end the main hanger member may have a vertically disposed slotted guide tube, and the lamp hanger mem- 15 ber a stem adapted to enter said guide, with means on said stem to enter the slot of the guide and carrying a latch dog engageable with a shoulder on the outside of the guide. The guide and stem parts being centrally 20 located, it will be apparent that the point of support in latched position will be eccentric of the main hanger members, so that unless a perfect fitting between guide and stem is had the lamp hanger member will not be 25 exactly plumb when latched. Contactors are carried by the main hanger members to be interengaged when the former parts are latched, and the contacts are impaired if the lamp hanger member is not plumb. Since it 30 is not practicable to machine the guide and stem parts for a close fit therebetween, it becomes necessary to provide other means for properly positioning the stem in the guide, and such is the object of this invention.

35 Further objects and advantages of the invention will be apparent from the following description, taken in connection with the accompanying drawings, wherein Figs. 1 and 2 are respectively front and side assembly 40 views of the parts, largely in elevation, but partly in section to show details of construction; Fig. 3 is a perspective view of the guide tube associated with the main hanger mem- 45 ber, partly broken away; and Fig. 4 is a sec- tional elevation of the latter on a central plane.

With reference to the drawings, the prin- 50 cipal parts of the main hanger member are a combination sheave and bracket 1 adapted to be secured upon a ceiling, a pair of con-

tactors 2 carried thereby and the guide tube 3 vertically positioned between the contactors 2.

The hanger member immediately supports a luminair 4, carries a pair of contactors 5 and has therebetween the stem 6. A chain 7 is bent over the sheave 8 of the main hanger member, passes downwardly therethrough and through the stem 6 which is hollow, and is secured therewith as at 9. Obviously by this chain the lamp hanger member may be raised to the position shown wherein the contact is made between the contactors 2 and 5, and may be lowered from this position when attention to the luminair is desired. The contactors 5 are yieldably supported on the lamp hanger member by an arrangement including the spring 10, and leads 11 carry from these contactors electric current supplied to the luminair.

The guide 3 is slotted on one side as at 12 to receive an arm 13, laterally extending from the stem 6, and the lower structure of the guide is diagonally disposed as at 14 to provide a cam cooperative with the arm 13 by which the contactors 2 and 5 are brought into registry as the stem 6 enters the guide.

Latch means are provided for maintaining the lamp hanger member in raised position and to this end a dog 15 is pivotally mounted 80 on the arm 13 as by the cotter pin 16, which dog has a protecting lip 17 movable inwardly of the stem by the weight of the other parts of the dog. The guide 3 on either side of its slot 12 is provided with a shoulder 18 co- 85 operative with the lip 17 of the dog. By this arrangement, when the chain 7 is manipulated to raise the lamp hanger member to uppermost position and then slowly released, the parts will latch and thereafter by a pull 90 upon the chain followed by a quick release thereof, unlatching of the lamp hanger member may be effected.

What has thus far been described is not new in the art but will be found set forth more in detail in my Patent No. 1,552,654, of September 8, 1925.

Where the guide and stem members 3 and 6 are to be of cast material it will be obvious that the general inner diameter of the guide 100

must be considerably greater than the diameter of the stem to allow for variations in castings. But since the support of the stem in latched position is had on one side of the center line of the parts, there will be a tendency to swing out of plumb, as to the left, Fig. 2, about the cotter pin 16.

To plumb the stem and consequently the lamp hanger member when latched, I provide upon the inner surface of the guide opposite the slot 12 and well above the shoulder 18, a boss 19. As appears from Figs. 3 and 4 this boss is arranged to present a curved or arcuate face eccentric of the general interior surface of the guide. Before latching, when the lamp hanger member is supported on the chain 7, the stem 6 has ample clearance in the guide 3, as it may if necessary tilt away from the boss 19. From Fig. 2 it will be apparent that when the parts are latched this face 19 will abut the upper extremity of the stem 6 to maintain the same plumb, bearing between stem and guide being then at 2 points, namely between dog and shoulder 18, and between stem and boss 19.

Immediately the lamp hanger member is again supported upon the chain 7, as during and after unlatching, the stem may pull away from the boss 19 and thus have ample clearance in the guide.

In order to exactly position the stem in the guide at the instant of the locking operation, I provide within the guide adjacent the shoulders 18, bosses 20 which together follow a curvature on the side of the slot 12 eccentric of the general interior of the guide.

On the lower extremity of the guide I may provide a third boss 21, against which the stem may first bear as it enters the guide, for the purpose of improving alignment of the contactors 5. This boss 21 however does not concern the described functioning of the bosses 19 and 20.

I have found the described arrangement of bosses to be much superior to an attempted exactly cylindrical opening in the guide, as accuracy in casting of these bosses may be maintained within much closer limits than average throughout the casting. Since each of the bosses is located upon one side only of the guide such accuracy in foundry work is made possible that no subsequent machining of the parts is required.

What I claim is:

1. In a lamp hanger, a main hanger member having a vertically disposed slotted guide tube, a lamp hanger member having a stem adapted to loosely fit within said guide, means associated with said main hanger member for raising and lowering said lamp hanger member to cause said stem to enter or leave said guide, an arm on said stem adapted to enter the slot of said guide, a latch dog carried by said arm, a shoulder on the outside of said guide engageable by said latch

dog to support said lamp hanger member in raised position, and means for maintaining said stem vertical in said guide when said dog is engaged, and comprising a boss within said guide at an elevation above said shoulder and on the side thereopposite only.

2. In a lamp hanger, a main hanger member having a vertically disposed cylindrical guide tube having a slot on one side, a lamp hanger member having a cylindrical stem adapted to loosely fit within said guide, means associated with said main hanger member for raising and lowering said lamp hanger member to cause said stem to enter or leave said guide, an arm on said stem adapted to enter the slot of said guide, a latch dog carried by said arm, a shoulder on the outside of said guide engageable by said latch dog to support said lamp hanger member in raised position, and a boss within said guide for bearing against said stem, said boss being on one side only of said guide and presenting a curved face eccentric of the general guide axis.

In testimony whereof I hereby affix my signature.

ALLISON J. THOMPSON.
